(No Model.)

J. BOLTON.
SEWING MACHINE TABLE.

No. 552,507.

Patented Jan. 7, 1896.

UNITED STATES PATENT OFFICE.

JAMES BOLTON, OF CHICAGO, ILLINOIS, ASSIGNOR TO THE SINGER MANUFACTURING COMPANY, OF NEW JERSEY.

SEWING-MACHINE TABLE.

SPECIFICATION forming part of Letters Patent No. 552,507, dated January 7, 1896.

Application filed April 10, 1893. Serial No. 469,779. (No model.)

To all whom it may concern:

Be it known that I, JAMES BOLTON, a citizen of the United States, residing at Chicago, in the county of Cook and State of Illinois, 5 have invented certain new and useful Improvements in Sewing-Machine Tables, of which the following is a specification, reference being had therein to the accompanying drawings.

10 My invention relates to sewing-machine tables or stands, and more particularly to that class thereof which are so constructed as to permit the sewing-machine, when not in use, to be dropped down below the surface of the 15 table, so that by folding down the leaf which forms an extension of the table, onto the surface of the latter, the opening in the table proper is covered, and thus the table is adapted for use as an ordinary table, this class of 20 stands being known to the trade as "drop-cabinets."

The object of my invention is to provide a brace for the class of sewing-machine stands or tables referred to, which brace is of such 25 construction that the driving-wheel of the machine may be mounted thereon and be out of the way of the operator, the brace being so made that it may be quickly and cheaply secured to the legs or side frames of the table, 30 and the screws by which the bottom portions of the brace are secured to the said legs or side frames serving also as center screw-bearings for the treadle. The bearing for the driving-wheel is of such construction that it may 35 be adjusted to compensate for wear.

In the accompanying drawings, Figure 1 is a front view of a sewing-machine stand embodying my invention, the legs or side frames of the stand and the table portion thereof 40 being denoted simply by dotted lines. Fig. 2 is a detail sectional view of the bearing for the driving-wheel. Fig. 3 is a detail sectional view of one of the bearings for the treadle, and Fig. 4 is a partial cross-section showing 45 the receptacle for the machine when the same is dropped beneath the table.

A A denote the legs or side frames of a sewing-machine stand or table, these being usually of cast-iron.

50 B is the table portion of the stand, and C denotes a receptacle beneath the table into

which the machine may be dropped when not in use.

The sewing-machine (denoted by dotted lines in Fig. 4) is mounted upon a hinged section b of the table B, said hinged section b being supported in front by a second smaller hinged section b', which, when the section b is lifted slightly, may be turned upward to permit the said section b with the sewing- 55 machine mounted thereon to fall down below the table B into the receptacle C in the direction denoted by the arrow in Fig. 4. The brace which connects the legs or side frames A, and which serves to stiffen and steady the 60 table, comprises the curved outer vertical parts or bars d and the horizontal bars d' d'', the latter having the extension d'''.

The outer ends of the upper horizontal bar d' are screwed or bolted to the side frames A 70 in any suitable manner, and the lower ends of the bars d are secured to the said legs or side frames by means of screws a, tapped through the said legs or side frames and passing loosely through the lower ends of the bars 75 d of the brace, the said screws being rounded or pointed at their inner ends to serve as center or bearing screws for the treadle E, which is mounted thereon, as more clearly shown in Fig. 3, set-nuts a' being provided to hold the 80 screws in any desired position of adjustment to firmly lock the lower ends of the brace to the legs or side frames of the table.

The upper horizontal arm d' serves as a support for the box or receptacle C, which 85 encloses the machine when the latter is dropped below the table. The part d''' of the lower horizontal bar d'' extends outside of one of the vertical bars d and is preferably formed conical at its outer end, as shown in Fig. 2, so that 90 it may fit in a correspondingly-shaped recess or countersink in the inner side of the hub of the driving-wheel F, the outer side of said hub being also countersunk for the reception of the conical head on the screw f, which is 95 tapped into the extension or bar d'', and which screw serves as a bearing for the said driving-wheel. The screw f may be turned, when desired, to compensate for wear at the hub of the driving-wheel, and is secured in any desired 100 position of adjustment by the set-screw f'.

By arranging the driving-wheel, as shown,

outside of one of the curved vertical bars of the brace, the latter, it will be observed, serves as a guard to prevent the dress of the operator from coming in contact with the driving-wheel 5 or with the pitman *g*, which connects said wheel to the treadle *E*.

It will thus be seen that by the simple form of brace herein shown and described I am enabled to provide an efficient compensating 10 bearing for the driving-wheel, and a bearing for the treadle as well as a dress-guard, while the brace itself, although simple in construction, serves as a support for the receptacle *C* and strongly braces the whole table and renders it firm and efficient. 15

Having thus described my invention, I claim and desire to secure by Letters Patent—

1. The combination with the table and legs 20 or side frames of a sewing machine stand provided with a receptacle into which the sewing machine may be dropped when not in use, of a brace connecting said legs or side frames and to the outer part of one side of which the

driving wheel is journaled, said brace having 25 an upper cross-bar serving as a support for said receptacle and being provided at its lower end with screws which serve to secure the same to said legs or side-frames of the stand and which also serve as bearing screws for 30 the treadle.

2. The combination with the legs or side frames of a sewing machine stand, of a table attached to the tops of said legs or side frames, a receptacle beneath said table into which the 35 sewing machine may be dropped when not in use, and a brace connecting said legs or side frames and to the upper part of one side of which the driving wheel is journaled, said brace having an upper cross bar serving as a 40 support for said receptacle, substantially as set forth.

In testimony whereof I affix my signature in presence of two witnesses.

JAMES BOLTON.

Witnesses:

HENRY CALVER,
CASSIE M. SWEENEY.
